UNITED STATES PATENT OFFICE.

JAMES R. PARRISH, OF NASHVILLE, TENNESSEE.

SOUND-MODIFYING DEVICE FOR PHONOGRAHS.

1,406,069.

Specification of Letters Patent. Patented Feb. 7, 1922.

Application filed May 3, 1921. Serial No. 466,392.

To all whom it may concern:

Be it known that I, JAMES R. PARRISH, a citizen of the United States, and a resident of Nashville, in the county of Davidson and State of Tennessee, have invented certain new and useful Improvements in Sound-Modifying Devices for Phonographs, of which the following is a specification.

This invention relates to a sound modifying device for phonographs.

The object of the invention is to provide a device of the above character which may be easily and expeditiously attached to the needle holder of a phonograph without changing the construction thereof, and when attached, adapted to soften and lower the volume of sound waves produced by the phonograph.

It is also an object of the invention that the device be adapted to in no way impair the clearness of the musical sounds produced by the phonograph with which it may be associated.

Other objects and objects relating to details of construction, combination and arrangement of parts will hereinafter more fully appear in the description to follow.

The invention is illustrated by way of example in the accompanying drawings, in which:

Figure 1 is a detail elevation of a phonograph diaphragm casing and associated parts and illustrating my invention when applied to the needle holder,

Figure 2 is a side elevation of the device, Figure 3 is a longitudinal transverse section of the same,

Figure 4 is a lower end view of the same, Figure 5 is an upper end view of the same,

Figure 6 is an upperface view of the same, and particularly illustrating the angular disposal of the stem for connecting the attachment to the needle holder of a phonograph,

Figure 7 is a plan view illustrating the disposal of the device when held by the needle holder of a phonograph, and

Figure 8 is a view similar to Figure 6, but showing a different angular disposal of the stem.

Referring to the drawings in detail, and particularly to Figures 1 to 7, 10 indicates a tone arm, 11 a diaphragm housing, 12 a stylus which terminates at its lower end in

the usual phonograph needle holder 13. 55 Also at 14 is shown the usual set screw for clamping the phonograph needle. At 15 is indicated the usual turn table which supports the disk record indicated at 16, and at 17 is indicated the usual turn-table spindle. 60

In carrying out my invention, I provide a supplemental needle holder generally indicated at A, Figures 3, 4 and 5, and a stylus extension generally indicated at B. The stylus extension B consists of a stem 18 65 which is preferably triangular in cross section so that the same may be inserted within the usual needle holder of phonographs. This stem terminates in an enlarged portion 19 which is semi-circular in cross section 70 and the peripheral surface of which is formed with a bead 20 at each end of the enlargement. The member A is preferably of the shape shown, and adapted to be fitted against the flat side of the portion 19 and 75 form therewith a peripheral surface which is oblong in cross section.

The member A is also slightly longer than the member B and its forward end extending from the member B, as shown. The extended end is formed with an enlargement 22, the inner edge of which is in alinement with the corresponding bead 20 of the member B. Also the member A is formed with a bead 23 on its opposite end, which is in 80 register or in alinement with the corresponding bead 20 of the member B. The member A is further formed with a longitudinal bore 24 which is adapted to accommodate the larger end of a phonograph needle. A 85 threaded opening 25 is provided centrally of the enlargement 22 and adapted for receiving the set screw 26 by which a needle placed within the bore 24 may be clamped.

Between the members A and B there is interposed a strip of rubber 27, said strip having the greater portion of its lower side surface offset and said offset portion adapted to accommodate a strip of felting 28, the felting being of the same width as the rubber strip 27. The members A and B are preferably secured together by wrapping a silk thread about the combined peripheral surfaces as indicated at 29, or by a rubber sleeve as shown in Figures 2 and 8, the 100 thread wrapping being preferable.

Referring to Figure 6, it will be seen that the stem 18 is disposed at a slight angle

with respect to a vertical plane passing through the members A and B, said plane being indicated by the dotted line 31. The object of this angular disposal of the arm 5 18 will be later made evident.

In the use of the present device, the stem 18 is positioned in the needle holder 13 and clamped by the means of a screw 14. A needle 32 is then positioned in the bore 24 10 of the member A and secured against removal by the set screw 26. By referring to Figure 7, it will be observed that the point of a needle 32 will contact with the record 16 at a point 33, and it will also be observed 15 that the reason for the needle point making contact at this particular point is due to the angular disposal of the stem 18. Should the stem 18 be straight then the point of contact of the needle 32 with the record 20 would fall at the point 34 which is of a greater distance from the center of the record 16. Now assuming that the stem 18 instead of terminating in the portion 19 of the member B that is terminated in a needle 25 point as indicated in dotted lines in Figure 7. If such were the case then the point of this needle would contact with the record at the point 35. It should now be observed 30 that the points 35 and 33 are of equal distance from the spindle 17 or center of the record 16. It therefore becomes obvious that by the angular disposal of the stem 18 the point 32 will be caused to engage with the same tangent relation with the grooves of 35 the record, as would the point of a needle when held by the needle holder 13.

It is believed from the foregoing description that the operation of the present device is clearly obvious. The purpose of the 40 rubber strip 27 and felting 28 is to reduce the vibrations transmitted from the needle 32 to the stylus 12. That is, by the use of my device, the vibrations transmitted to the stylus 12 will be perceptibly less than if the 45 phonograph needle was directly connected to the phonograph holder 13. It may also be pointed out that the clearness of tone will in no way be impaired, and likewise to a cer-

tain extent the scratching noise of the needle will be reduced.

Referring to Figure 8, it will be observed 50 that the stem 18 is bent downwardly with respect to a horizontal plane passing centrally of the members A and B. By such a construction the inclination of the needle 32 55 with respect to the record 16 may be increased, that is, may be inclined toward the vertical. I have found by experiment that when this inclination is increased that the sharpness of the tone produced will likewise 60 be increased and hence the reason for this construction. It is to be understood however that this is merely a modified form of my invention, and that the construction as set out in Figures 1 to 7 inclusive is the 65 preferred one.

While I have shown and described the preferred form of my invention, it is to be understood that I am aware of the fact that the construction, combination and arrangement 70 of parts may be changed by those skilled in the art without departing from the spirit of my invention, as indicated by the appended claims.

I claim:—

1. A sound modifying device for phonographs, comprising a needle holder, a stem, a non-metallic material interposed between said stem and needle holder, and non-metallic means for binding the needle holder 80 and stem together.

2. A sound modifying device for phonographs, comprising a needle holder, a stem, a non-metallic material interposed between 85 said stem and needle holder, and a thread wrapped about said stem and needle holder for binding the same together.

3. A sound modifying device for phonographs, comprising a needle holder, a stem, a non-metallic material interposed between 90 said stem and needle holder, and a non-metallic thread wrapped about said needle holder and stem for securing the same together.

JAMES R. PARRISH.
